UNITED STATES PATENT OFFICE.

GEORGE A. RICKER, OF BUFFALO, NEW YORK.

DESIGN FOR A BRACKET FOR ELECTRIC WIRES AND CABLES.

SPECIFICATION forming part of Design No. 35,029, dated September 3, 1901.

Application filed May 10, 1901. Serial No. 59,711. Term of patent 3½ years.

To all whom it may concern:

Be it known that I, GEORGE A. RICKER, a citizen of the United States, residing in the city of Buffalo, in the county of Erie and State 5 of New York, have invented and produced a new and original Design for Brackets for Electric Wires and Cables, of which the following is a full, clear, and exact description.

My invention relates to a design for brackets for electric wires and cables; and it consists, essentially, of the construction shown in the drawings herewith, in which like characters of reference indicate like parts.

Figure 1 is a perspective view. Fig. 2 is 5 an end elevation. Fig. 3 is a front elevation.

The design consists of a hollow cylindrical body A and a box-bracket B. The cylindrical casting is split longitudinally, as shown at a, one half being cast integrally with the box-bracket B and the other half separately. The box-bracket B is webbed to the cylindrical body at b and the other half of the cylindrical body is provided with ears c, which

face against the box-bracket B. The ears c have bolt-holes d concentric with bolt-holes 25 in the box-bracket B. The cylindrical body A engages an insulating-spool C, which is split longitudinally to correspond to the split in the body A, as shown at e. The ends of the spool C are flanged to take over the ends 30 of the body A. The box-bracket B is provided with bolt-holes, as shown in broken lines in Fig. 2.

Having thus described my invention, what I claim is—

The design for a bracket for electric wires and cables, substantially as shown and described.

In witness whereof I have hereunto set my hand, in the presence of two witnesses, this 40 25th day of April, 1901, at the city of Buffalo, in the county of Erie and State of New York.

GEORGE A. RICKER.
